SIGN OR SIMILAR ARTICLE

Kenneth F. Smith, Lima, Ohio, assignor to Neon Products, Inc., Lima, Ohio, a corporation of Ohio

Application July 13, 1949, Serial No. 3,886

Term of patent 14 years

(Cl. D1—12)

To all whom it may concern:

Be it known that I, Kenneth F. Smith, a citizen of the United States, residing at Lima, Allen county, State of Ohio, have invented a new, original, and ornamental Design for a Sign or Similar Article, of which the following is a specification, reference being had to the accompanying drawing, forming part thereof.

In the drawings,

Figure 1 is a view in front elevation of a sign, showing my new design; the opposite side is similar;

Fig. 2 is a top plan view; the bottom is similar; and

Fig. 3 is a view in end elevation; the opposite end is similar.

I claim:

The ornamental design for a sign or similar article, as shown.

KENNETH F. SMITH.
